UNITED STATES PATENT OFFICE

HARRY F. WOERNLEY, OF WILKINSBURG, PENNSYLVANIA, ASSIGNOR TO THE WESTINGHOUSE AIR BRAKE COMPANY, OF WILMERDING, PENNSYLVANIA, A CORPORATION OF PENNSYLVANIA

PORTABLE PRESS

Application filed January 19, 1929. Serial No. 333,667.

This invention relates to portable devices or tools and has for its principal object to provide a portable press for use in assembling or disassembling draft gears, particularly friction draft gears.

Other objects and advantages will appear in the following more detailed description of the invention.

In the accompanying drawings, Figure 1 is a plan view of a portable press embodying my invention; Fig. 2 is a side elevational view of the same; Fig. 3 is a side elevational view of the press in its vertical position; and Fig. 4 is a part plan view of a modification of the invention.

As shown in the accompanying drawings, my portable draft gear press may comprise a single integral frame member made in the form of a yoke having transversely spaced side pieces 1, longitudinally spaced end pieces 2 and 3 and cross pieces 4 and 5 spaced from each other and from the end pieces 2 and 3.

Intermediate the side pieces 1, the cross pieces are offset outwardly, the offset portions supporting a plate 6 which is preferably perforated so that dirt will not collect on the plate.

The end piece 2 is made deep so as to provide a wide substantial base for the press when said press is placed in a vertical position as shown in Fig. 3 of the drawings.

Depending downwardly from the end piece 2 and the cross piece 4 are transversely spaced vertical lugs 7 in which an axle 8 is mounted, the ends of said axle having wheels 9 rotatably mounted thereon through the medium of which the press may be transported from one place to another.

At the rear end of the frame there is a pressure device such as a screw-jack 10 having its housing 11 secured to the end piece 3 of the frame by a bolt 12 and nuts 13. This jack may be of the usual screw type having its screw-threaded pressure member 14 disposed longitudinally of the frame and its op-

erating shaft 15 disposed upwardly at a right angle thereto.

Secured to the frame and extending rearwardly therefrom is a handle 16.

In operation, the press is transported, on its wheels, to any desired location and then moved to a vertical position, in which the end piece 2 rests upon the ground or floor, thus supporting the frame in a vertical position as shown in Fig. 3 of the drawings. When the frame is in this position the wheels 9 are out of contact with the ground or floor.

With the press thus positioned, a draft gear 23 that is to be assembled or disassembled may now be placed therein. In placing the draft gear, the end of the draft gear casing will rest on the inner flat surface of the end piece 2 and one of the side walls of the casing will contact with the plate 6, or with the cross pieces 4 and 5 if the plate 6 is omitted. The side pieces 1 are so spaced and the cross pieces 4 and 5 offset to such an extent, that when the draft gear is so placed, the center thereof will be substantially in alignment with the axis of the pressure member 14 of the jack.

When the draft gear is properly placed, the operating shaft 15 is rotated, by means of a bar inserted in an opening 17 formed in the shaft, which causes the screw-pressure member to move downwardly until a plate 18 mounted on the lower end thereof engages the frictional elements 19 and 20 of the draft gear. The continued operation of the jack causes these friction members to be moved downwardly against the pressure of the usual draft springs (not shown) which are contained in the draft gear casing, so that if the draft gear is to be disassembled, the key 21 which holds the draft gear parts together, may be removed or if the draft gear is being assembled, the key may be inserted.

After the key 21 is thus removed or inserted, as the case may be, the jack is operated to relieve the draft gear of pressure, when the

draft gear parts may be removed in case the gear is to be disassembled, or the draft gear parts secured together as a unit may be removed in case the gear has been assembled.

5 If it should be desired to transport the draft gear or draft gear parts to another place, instead of removing them from the press when said press is in its vertical position, the press may be tilted so that the 10 wheels are again in engagement with the ground and floor and the end piece 2 is out of engagement therewith, when a workman 15 may, through the medium of the handle 16 move the press on its wheels to the desired location.

15 While I have described the press as being in a vertical position to compress the draft gear, which is the preferred position, it will be understood that it may be used in a horizontal or any other position. In using the 20 press in any position other than a vertical position, the wheels would probably have to be chocked.

25 In Fig. 4 of the drawings a modification of the invention is shown, in which the jack housing 22 is made an integral part of the frame of the press.

30 In the foregoing description the frame of the press has been described as a single integral piece, but it is to be understood that it may be built of a number of pieces suitably secured together.

35 While two illustrative embodiments of the invention have been described in detail, it is not my intention to limit its scope to these embodiments or otherwise than by the terms of the appended claims.

40 Having now described my invention, what I claim as new and desire to secure by Letters Patent, is:—

1. In a portable press, the combination with a frame adapted to receive a draft gear, said frame having an end piece adapted to support the press in a vertical position and 45 forming a seat for one end of said gear, of means carried by said frame adapted to be operated into engagement with the other end of said gear to compress the gear, and wheels upon which said press is transported when the press is moved from a vertical position.

50 2. In a portable press for compressing draft gears in assembling and disassembling said gears, the combination with an integral frame adapted to receive a draft gear, said frame comprising side pieces and end pieces, one of said end pieces forming an abutment for one end of said draft gear, of means carried by the other of said end pieces operative to engage the other end of said draft gear to 55 compress the gear.

60 3. In a portable press for compressing draft gears in assembling and disassembling said gears, the combination with an integral frame comprising side pieces and end pieces between 65 which a draft gear may be inserted, one of

said end pieces forming an abutment for one end of a draft gear positioned between said pieces and also a support for said press when the press is in a vertical position, of means carried by the other of said end pieces and operative to exert pressure on the other end of said gear, and wheels carried by said frame upon which said press may be transported when said frame is tilted from its vertical position.

70 In testimony whereof I have hereunto set my hand, this 16th day of January, 1929.

HARRY F. WOERNLEY.
